UNITED STATES PATENT OFFICE.

JOSEPH ISGRO AND DOMINICK MONDI, JR., OF JOHNSTOWN, PENNSYLVANIA.

AUTOMATIC CAR-STEP REGISTER.

Application filed July 17, 1923. Serial No. 652,043.

To all whom it may concern:

Be it known that we, (1) JOSEPH ISGRO and (2) DOMINICK MONDI, Jr., (1) a subject of the King of Italy and (2) a citizen of the 5 United States, both residing at Johnstown, in the county of Cambria and State of Pennsylvania, have invented certain new and useful Improvements in Automatic Car-Step Registers, of which the following is a specification.

In carrying out the present invention, it is our purpose to provide a register actuating mechanism for cars, trains and the like, that is automatic in its nature, for thereby 15 overcoming the necessity of the car or train conductor actuating said register upon the entrance of individual passengers into the car.

The primary object of our invention resides in the provision of such an actuating mechanism for car registers wherein the entrance doors of the cars are equipped with compressible steps that are operatively connected to the pull cords of the register for 25 thereby operating the same every time a passenger engages upon the step of the entrance door.

A still further object of the invention is to provide such a register actuating mechanism for cars that is extremely simple of 30 construction and efficient in operation, and of such a nature as to be readily associated with practically all types of cars, trains and the like now in use.

The nature and advantages of the invention will be better understood when the following detailed description is read in connection with the accompanying drawings, the invention residing in the construction, 35 combination and arrangement of parts as claimed.

In the drawings forming part of this application, like numerals of reference indicate similar parts in the several views, and 40 wherein:

Figure 1 is a detail transverse cross section of this actuating mechanism, per se.

Figure 2 is a longitudinal cross section thereof, and

50 Figure 3 is a view similar to Figure 1 of a type of actuating mechanism for electric registers.

Now, having particular reference to the drawings, A designates a wellknown type of 55 street car provided with inlet openings B at the front and rear ends and at opposite sides

thereof. We have shown this device as associated with a street car, but it is to be understood that we do not wish to be limited to such a showing as the mechanism may be 60 applied to all types of conveyances employing a fare or passenger register.

In Figure 2, C indicates the floor of the car, while D indicates the usual step beneath the level of said floor and joined thereto by 65 a skirt portion E.

Our novel register actuating mechanism comprises an auxiliary step 5 that embodies a major top longitudinal portion 6 and a front pendent skirt portion 7. The rear 70 end of the said major portion 6 engages through a longitudinal slot 8 in the connecting portion E between the floor C and step D of the car, it being noticed from a consideration of Figure 2 that this is of greater 75 width than the thickness of said major portion of the step 5. The lower edge of this slot is rounded at 9 for reception within a rounded longitudinal channel 10 upon the undersurface of the portion 6 of the step 80 for providing a pivotal connection between said step and said connecting portion E of this floor and step C and D, respectively, of the car A.

The step D of the car is formed with a 85 pair of pockets d adjacent opposite ends thereof for receiving the lower ends of relatively strong expansible coiled springs 11 that engage at their upper ends beneath the major portion of the auxiliary step 5 for 90 normally maintaining this step in the elevated position of Figure 2.

At a point intermediate the pair of springs 11 and secured to the top face of the car step D adjacent the front edge thereof 95 in any manner desirable, is a metallic plate 12, that is formed at its rear end with a pair of upstanding flanges 13, between which is positioned the lower end of an upwardly extending curved bar 14. The upper end of 100 this bar is curved forwardly and has contact with a metal plate 15 upon the underside of the major portion 6 of the auxiliary step 5 at its front end. The pendent skirt portion 7 of this step 5 adjacent the forward 105 end of said plate 15 is socketed at 15, for receiving the bent end of the curved bar 14 when the step 5 is depressed.

The cord or cable 17 that is operatively connected to the register of the street car (not 110 shown) is connected at its front end to the bar 14 at the upper end thereof, and extends

2
through an opening 18 in the connecting portion E between the floor C and step D of said car A.

In view of the foregoing when considered in conjunction with Figures 2 and 3 of the drawings, it will be at once apparent that upon the entrance of each passenger into the car, the step 5 will be depressed by the weight of the passenger, thereby forcing the 10 arm forwardly and consequently pulling upon the cable 17 which will operate the register of the car.

In Figure 4, there is shown a means for operating the electrical registers sometimes found upon cars or trains and in this instance the auxiliary step 5' is equipped at a point substantially as shown with one contact 19 of a switch, while the step D' of the car is equipped at a point directly beneath 20 said contact 19 with a spring contact 20, that is upon the upper end of a support 20. The contact 19' has electrical connection with a suitable source of supply F, while the other contact is electrically connected to the street 25 car register, it being also of course apparent that the source of supply F is also connected to said register, whereby a depression of the step 5' will complete the circuit between the source of supply and the register for actuating the same.

Numerous advantages of a device of this character will be readily appreciated by those skilled in the art, and even though we have herein shown and described the most

preferred embodiment of the present invention with which we are at present familiar, it is nevertheless to be understood that minor changes may be made therein, without departing from the spirit and scope of the invention as claimed.

Having thus described our invention, what we claim as new, and desire to secure by Letters Patent, is:

A step structure having a tread portion, and a riser, the riser having a longitudinal slot, the lower edge wall of which is curved transversely, a panel passing through the slot, and having at its under side a groove, which receives the said curved edge wall, a spring interposed between the tread and the 50 panel and serving to normally hold the free edge of the panel elevated with relation to the tread, a plate mounted at the under side of the panel and at the free edge thereof, a plate mounted upon the upper surface of the 55 tread portion of the step and having spaced flanges, a longitudinally curved bar having its lower end received between the flanges of the last mentioned plate and its upper end bearing against the under side of the plate upon the panel, and a pulling element passing transversely through the riser and connected with the bar in the vicinity of the upper end thereof.

In testimony whereof we affix our signatures.

JOSEPH ISGRO.
DOMINICK MONDI, JR.
